BRASSIÈRE

Edwin W. Gluckin, Brooklyn, N. Y.

Application September 30, 1944, Serial No. 556,604

12 Claims.

(Cl. 2—42)

This invention relates to brassières of the type and kind employed to support the breasts in raised youthful position, while at the same time, providing a brassière which will adapt itself to variations in the spacing of the breasts on the body of the wearer, and at the same time, compensating for expansion and contraction of the chest when the brassière is in use. Still more particularly, the invention deals with brassières of the kind under consideration employing yieldable straps extending from the lower central portion of the brassière pockets to the upper central portion of an opposed pocket and arranged in cross relationship to each other centrally of the brassière and intermediate the breasts of the wearer. Still further, in providing elastic or other straps extending from the central lower portion of each breast pocket to the outer edges of the pocket in firmly and yet yieldably supporting adjacent portions of the pockets upon the breasts of the wearer. The novel features of the invention will be best understood from the following description when taken together with the accompanying drawing, in which certain embodiments of the invention are disclosed, and in which the separate parts are designated by suitable reference characters in each of the views, and in which:

Fig. 1 is a front perspective view of a brassière made according to my invention.

Fig. 2 is a perspective view of the inside portion of the front of the brassière in extended position, with parts of the construction broken away; and

Fig. 3 is a perspective view of the lower portion of one pocket of the brassière showing the parts in separated condition to illustrate the relationship of free portions of the garment.

In the construction of brassières, efforts have been made to support the breasts in raised youthful form by providing in the breast pockets of the brassière various types and kinds of reinforcing members, stays and the like, but these devices have been objectionable, first from the standpoint of the stiffness or rigidity of the supporting means, rendering the garment uncomfortable to the wearer, as well as from the standpoint of the complication in the brassière structure and the added cost of constructing the same.

I overcome these objections by simply providing a dart in the central lower portion of a sheet of material to give the desired contour to each pocket, and leave lower edge portions of each pocket free to move relatively to each other, and then attach strap members to each free edge por-

tion extending one to the outer side edge of the breast pocket and the other to the upper central portion of an opposed pocket. These straps preferably include elastic or yieldable properties in order to prevent binding, and also to compensate for expansion and contraction of the chest in the use of the brassière.

In Fig. 1 of the drawing is illustrated diagrammatically in perspective, the general arrangement 10 of a brassière as it might appear upon the body of a wearer. The brassière comprises two front pockets 10 and 11 which are substantially of the same construction and are joined in a central seam 12, which is considerably less in height than the full height of the pockets 10 and 11. The pocket 10 has a side and back band portion 13, and the pocket 11 a similar portion 14. These portions are detachably coupled together in any desired manner, as at 15. As this coupling forms no part of the present invention, it is not shown in detail. However, these couplings are adjustable as to size, and usually comprise hooks engaging corresponding eye or socket portions which are arranged longitudinally of the coupling tab 16, the hooks being connected with the band portion 13. Shoulder straps 17 are attached to the top central portion of each pocket 10 and 11, and to the rear end portions of the bands 13 and 14, as will clearly appear from a consideration of the drawing. These shoulder straps have the usual adjustable buckles as at 18.

While the pockets 10 and 11 may be of any desired design and construction, from the standpoint of material and trimming, in the present construction, each pocket is made from a single sheet of material shaped to conform with the breast by darts 19 and 20 which extend down to the points 21 and 22.

Considering Fig. 3 of the drawing which shows the lower edge portion of the pocket 11, it will appear that this leaves the lower edge portions 23 and 24 of the pocket free to move relatively to each other. The same is true with the lower edge portion of the pocket 10, but as this structure is not clearly illustrated, no specific references are applied on the pocket 10. The inner surfaces 25 of the pockets may also have facings of net material or any other material suitable to engage the breasts of the wearer. Attached to the free portion 23 or the equivalent thereof on each pocket, is a lastex or other elastic member 26 which is secured to the side seam 27, where the pockets 10 and 11 join the bands 13 and 14. The members 26 are arranged upon outer surfaces of

the pockets 10 and 11, as will clearly appear from a consideration of Fig. 1 of the drawings.

Attached to the other free end portion 24, or the equivalent thereof on both pockets, is a wide tab 28 to which is joined a strap, the strap of the pocket 10 being designated by the numeral 29 and the strap of the pocket 11 being designated by the numeral 30. These straps extend out through apertures 31 and 32 respectively in said pockets and cross centrally of the brassière, as at 33, and then extend upwardly and are attached to elastic straps 34 and 35 respectively, the latter being attached to the upper corner portions of the opposed pockets, as at 36 and 37.

From the foregoing construction, it will be apparent that the breasts, when arranged in the pockets 10 and 11, will be supported in raised youthful position by straps 29 and 30, and the tabs 28 which actually extend the lift from the side seams 27 of one pocket directly to the upper central portion of the opposed pocket to be taken up directly by the shoulder strap. The elastics 34 and 35 provided in these straps give a certain amount of resiliency to prevent binding, and also to compensate for variations in the breasts and in relative positions thereof. The tabs 28 are preferably made quite large in order to fit beneath the lower, and or inner adjacent portions of the breasts, and these tabs may be composed of felt, or may be faced with any suitable soft material. The lastex or other members 26 operate to adapt the brassière to variance in sizes, and also to drawing the inner adjacent portions of the breast pockets tightly around the breasts. In other words, as illustrated in Fig. 3, the free ends 23 and 24 are free to move relatively to each other in mounting the brassière upon the body of the wearer and also in compensating for expansion and contraction of the chest when the garment is in use.

The crossing of the straps 29 and 30 centrally of the garment also tends to maintain the garment upon the body of the wearer intermediate the breasts, and in this respect, further amplifies the youthful contour of the breasts. While the garment will serve to support the breasts firmly in position, at all times, this support is on the other hand not a binding support, by reason of the elastic members employed for the purposes stated.

Having fully described my invention, what I claim as new and desire to secure by Letters Patent is:

1. A brassière of the class described comprising a pair of similar breast pockets, means joining adjacent edge portions of the pockets, means attached to outer side edges and upper portions of the pockets for adjustably supporting the same upon the body of the wearer, each pocket having centrally of the lower portion thereof free relatively movable parts, straps coupled with said free parts, said parts being continuous with inner and outer side portions of each pocket, the strap of the inner part extending to and being secured to the outer side edge of the pocket, and the strap of the outer part extending to and being secured to the upper central portion of an opposed pocket.

2. A brassière of the class described comprising a pair of similar breast pockets, means joining adjacent edge portions of the pockets, means attached to outer side edges and upper portions of the pockets for adjustably support-

ing the same upon the body of the wearer, each pocket having centrally of the lower portion thereof free relatively movable parts, straps coupled with said free parts, said parts being continuous with inner and outer side portions of each pocket, the strap of the inner part extending to and being secured to the outer side edge of the pocket, the strap of the outer part extending to and being secured to the upper central portion of an opposed pocket, and the last named straps of said pockets being crossed centrally of the front of the brassière.

3. A brassière of the class described comprising a pair of similar breast pockets, means joining adjacent edge portions of the pockets, means attached to outer side edges and upper portions of the pockets for adjustably supporting the same upon the body of the wearer, each pocket having centrally of the lower portion thereof free relatively movable parts, straps coupled with said free parts, said parts being continuous with inner and outer side portions of each pocket, the strap of the inner part extending to and being secured to the outer side edge of the pocket, the strap of the outer part extending to and being secured to the upper central portion of an opposed pocket, and the last named straps of said pockets being crossed centrally of the front of the brassière.

4. A brassière of the class described comprising a pair of similar breast pockets, means joining adjacent edge portions of the pockets, means attached to outer side edges and upper portions of the pockets for adjustably supporting the same upon the body of the wearer, each pocket having centrally of the lower portion thereof free relatively movable parts, straps coupled with said free parts, said parts being continuous with inner and outer side portions of each pocket, the strap of the inner part extending to and being secured to the outer side edge of the pocket, the strap of the outer part extending to and being secured to the upper central portion of an opposed pocket, and the last named straps of said pockets being crossed centrally of the front of the brassière, and means in the last named straps providing longitudinal extensibility thereof.

5. A brassière of the class described comprising a pair of similar breast pockets, means joining adjacent edge portions of the pockets, means attached to outer side edges and upper portions of the pockets for adjustably supporting the same upon the body of the wearer, each pocket having centrally of the lower portion thereof free relatively movable parts, straps coupled with said free parts, said parts being continuous with inner and outer side portions of each pocket, the strap of the inner part extending to and being secured to the outer side edge of the pocket, the strap of the outer part extending to and being secured to the upper central portion of an opposed pocket, and the last named straps joining said outer parts in wide pad portions.

6. A brassière of the class described comprising a pair of similar breast pockets, means joining adjacent edge portions of the pockets, means attached to outer side edges and upper portions of the pockets for adjustably supporting the same upon the body of the wearer, each pocket having centrally of the lower portion thereof free relatively movable parts, straps coupled with said

free parts, said parts being continuous with inner and outer side portions of each pocket, the strap of the inner part extending to and being secured to the outer side edge of the pocket, the strap of the outer part extending to and being secured to the upper central portion of an opposed pocket, said last named straps joining said outer parts in wide pad portions, and both of said straps having longitudinally extendible properties.

7. A brassière of the class described comprising breast pockets, means for supporting the pockets on the body of a wearer, each pocket comprising lower relatively movable inner and outer sides terminating in free edges centrally of the pocket, means extending from the free edge of the outer side portion of each pocket to the upper central portion of an opposed pocket for supporting the breasts of a wearer in raised youthful position in said pockets, and said means comprising a pair of straps crossed centrally of the brassière intermediate said pockets.

8. A brassière of the class described comprising breast pockets, means for supporting the pockets on the body of a wearer, each pocket comprising lower relatively movable inner and outer sides terminating in free edges centrally of the pocket, means extending from the free edge of the outer side portion of each pocket to the upper central portion of an opposed pocket for supporting the breasts of a wearer in raised youthful position in said pockets, said means comprising a pair of straps crossed centrally of the brassière intermediate said pockets, and said straps extending outwardly through slits in inner adjacent portions of said pockets.

9. A brassière of the class described comprising breast pockets, means for supporting the pockets on the body of a wearer, each pocket comprising lower relatively movable inner and outer sides terminating in free edges centrally of the pocket, means extending from the free edge of the outer side portion of each pocket to the upper central portion of an opposed pocket for supporting the breasts of a wearer in raised youthful position.

in said pockets, said means comprising a pair of straps crossed centrally of the brassière intermediate said pockets, said straps extending outwardly through slits in inner adjacent portions of said pockets, and means involving elastic straps attached to free edges of the inner adjacent lower portions of the pockets for firmly and yieldably supporting the breasts of a wearer.

10. In brassières of the class described comprising a pair of pockets with means for supporting the same upon the body of a wearer, the central lower portion of each pocket comprising relatively movable parts having free edges, strap members extending from the free edges of said parts, one strap member being attached to the outer side edge of the pocket and the other strap member being attached to the upper central portion of an opposed pocket.

11. In brassières of the class described comprising a pair of pockets with means for supporting the same upon the body of a wearer, the central lower portion of each pocket comprising relatively movable parts having free edges, strap members extending from the free edges of said parts, one strap member being attached to the outer side edge of the pocket and the other strap member being attached to the upper central portion of an opposed pocket, and the last named strap member extending through a slit on the inner portion of the pocket.

12. In brassières of the class described comprising a pair of pockets with means for supporting the same upon the body of a wearer, the central lower portion of each pocket comprising relatively movable parts having free edges, strap members extending from the free edges of said parts, one strap member being attached to the outer side edge of the pocket and the other strap member being attached to the upper central portion of an opposed pocket, and the last named strap member extending through a slit on the inner portion of the pocket, and both of said strap members being longitudinally extensible.

EDWIN W. GLUCKIN.
